UNITED STATES PATENT OFFICE.

JOHN PENROD AND ROBERT D. THOMPSON, OF OKMULGEE, OKLAHOMA.

SAND SWAB.

Application filed August 20, 1921. Serial No. 496,863.

To all whom it may concern:

Be it known that we, JOHN PENROD and ROBERT D. THOMPSON, citizens of the United States, residing at Okmulgee, in the county 5 of Okmulgee, State of Oklahoma, have invented a new and useful Sand Swab, of which the following is a specification.

This invention aims to provide novel means for swabbing the sand from a pump 10 plunger and to prevent sand from settling about the plunger, the settling sand being directed into the sand pocket. The invention aims, further, to provide a device of the sort mentioned, the parts of which are 15 spring-constrained to fit about the plunger closely, to the end that wear may be taken up.

The device forming the subject matter of this application is adapted to be used in 20 connection with a pump of the sort shown in a co-pending application, Serial No. 457,736, filed April 1, 1921.

We do not bind ourselves to the specific forms depicted and described, since a 25 mechanician may make changes, within the scope of what is claimed, without departing from the spirit of the invention or avoiding the charge of infringement.

In the drawings:—Figure 1 shows in longitudinal section, a device constructed in accordance with the invention; Figure 2 is an elevation showing the swab and the plunger; Figure 3 is a cross section on the line 3—3 of Figure 1; Figure 4 is a longitudinal 35 section showing a modification; Figure 5 is cross section on the line 5—5 of Figure 4; Figure 6 is a longitudinal section showing the application of the invention to the pump mentioned above and disclosed in the 40 co-pending application alluded to.

Referring to Figure 6, the numeral 1 indicates an outer pump casing having internal threads 86 at the opposite ends thereof, the threads at the lower end of the casing 45 being designed to accommodate a coupling 87 which connects a screen 88 to the casing. The threads 86 at the upper end of the casing 1 hold a coupling 89 carrying the tubing 90. The coupling 87 is provided with 50 a threaded opening 91 receiving the lower end of a working barrel 2, the upper end of the working barrel terminating in spaced relation to the coupling 89, so that particles of sand in suspension in the fluid handled by 55 the pump may settle into the sand trap 75

existing between the working barrel 2 and the casing 1. Located in the lower end of the working barrel 2 is a standing valve 92, which is of the usual type, the valve opening on the suction stroke, and closing on the 60 down stroke. The plunger is denoted by the numeral 11 and is provided with cups 93, affording a close fit between the plunger and the working barrel. The plunger 11 is provided with a housing 231 for a valve 65 94, the valve preferably being in the form of a ball, the upward movement of which is restricted by a transverse pin 95 carried by the plunger 11. A cage 96 is mounted on the upper end of the plunger 11 and an 70 operating member 97 is connected thereto. A valve 98 operates in the cage 96. The details above alluded to are shown in the co-pending application above mentioned and are reviewed in this application in order 75 that the utility of the device forming the subject matter of this application may be manifest.

The working barrel 2 has a circumferential seat 3, a support being mounted in the 80 seat. The support includes a pair of approximately semi-circular members 4 having outstanding ears 5 connected by tightening devices 6, such as bolts. The members 25 4 of the support are supplied with outstanding fingers 7. The fingers 7 and the ears 5 engage the casing 1 and thus the working barrel 2 is steadied and centralized in the casing.

The device includes a tubular collar 9 90 provided with a bore 10 wherein the plunger 11 is mounted for reciprocation, the collar of swab being equipped in its lower end with a seat 12 receiving the upper end of the working barrel 2. The tubular swab 9 95 has a flared mouth 14 at its upper end, the mouth leading to the bore 10. Openings 15 are formed in the upper end of the swab 9 and communicate at their inner ends with the flared mouth 14. Openings 150 are 100 formed in the swab 9 at the place where the mouth 14 joins the bore 10, the openings being located partly in the mouth and partly in the bore. The openings 15 slant downwardly and outwardly and sand which 105 might otherwise collect on the plunger 11 is received in the openings 15 or 150 and is directed downwardly into the sand pocket 75. Since the openings 150 intersect the bore 10, a plurality of sharp edges are formed and 110

these edges tend to strip from the plunger 11 any sand which may adhere thereto, and to direct into the opening 150, any sand which may not have passed downwardly 5 and outwardly through the openings 15.

The swab 9 consists of two trough-shaped members 16 having depending arms 17 provided with openings 18, the arms being received between the ears 5 of the support, the 10 openings 18 receiving the bolt 6, the members 16 of the swab thus being mounted pivotally on the support. Recesses 19 are formed in the member 16 of the swab, and define flanges 20, through which connections 15 21, such as bolts, extend. Compression springs 23 surround the bolts 21 and abut against the adjacent flanges 20 and against nuts 22 on the bolt. The springs 23 serve to draw the members 16 of the swab 9 about the 20 plunger 11, automatic compensation for wear being the result. The springs 23 may be adjusted by means of the nuts 22.

The members 16 of the swab 9 are provided on their longitudinal edges with lugs 25, the lugs on one member alternating with the lugs on the other member. The lugs 25 aid in preventing longitudinal shifting movement between the members 16 of the swab. The upper surfaces of the lugs 25 are 30 downwardly inclined, as shown at 26. Consequently, sand is carried downwardly and outwardly and does not tend to work inwardly between the lugs 25 into the bore or the swab to the obvious detriment of the 35 swab and the reciprocating plunger 11.

In the modification shown in Figures 4 and 5, parts hereinbefore described are designated by numerals previously used, with the suffix "a." In the modification, the 40 bolts 21 and the springs 23 are replaced by a single coiled prehensile spring 30 located in a circumscribing groove or seat formed in the members 16^a. Further, the holes 150 and 15 are replaced by openings of a different 45 sort, namely, slits 27 formed in the upper ends of the members 16^a, the slits being downwardly and outwardly inclined as shown at 27^a. The operation of the form shown in Figures 4 and 5 will be understood 50 from what has been stated hereinbefore concerning the form set forth in Figure 1.

What is claimed is:—

1. In a device of the class described, a casing, a working barrel within the casing, a plunger operating within the working barrel, a sand trap mounted on the working barrel and comprising members mounted for movement toward and away from each other; and spring means for moving said members toward each other. 55

2. In a pumping apparatus, a casing, a working barrel within the casing and spaced therefrom to provide a sand trap, a plunger operating within the working barrel, a sand swab mounted on the working barrel and comprising members mounted for movement toward and away from each other, said members having interengaged lugs, the upper surfaces of which are downwardly and outwardly inclined; and spring means for 60 moving said members toward each other. 70

3. In a pumping apparatus, a casing, a working barrel within the casing, a plunger operating within the working barrel, a sand swab having a central bore to permit the 75 swab to be positioned on the working barrel, and plunger, said swab being provided with a flared mouth communicating with the bore, the swab having downwardly and outwardly inclined openings in that end which is provided with the mouth, the swab comprising members mounted for movement toward and away from each other; and means for moving said members toward each other. 80

4. In a device of the character described, 85 a casing, a working barrel supported within the casing, a plunger operating within the working barrel, a sand swab supported by the working barrel and adapted to frictionally engage the plunger, said swab comprising cooperating members mounted for relative transverse movement with respect to each other; and means for adjusting said members transversely with respect to each other. 90

In testimony that we claim the foregoing as our own, we have hereto affixed our signatures.

JOHN PENROD.
ROBERT D. THOMPSON.
